DIRECT READING MICROMETER

Walter A. Bohn, Lakewood, Ohio, assignor to
Master Products Company, Cleveland, Ohio, a
corporation of Ohio

Application July 13, 1934, Serial No. 734,964

5 Claims. (Cl. 33—147)

This invention relates to micrometers, and particularly to those that are known in the trade, as the direct-reading type. Micrometers of this character are used for production work in gauging large quantities of sheet metal with rapidity, particularly during the sorting operation, while the metal is being transferred from a conveyance to a warehouse.

The usual C-clamp hand-operated micrometer is objectionable for production work, as outlined, for it necessitates an objectionable length of time to use it, and for the further reason that it can be sprung if excessive pressure is used on the operating stem. An effort has been made to produce a direct-reading micrometer, but so far as I am aware, none has been produced, in which the jaws engage the work under hand pressure, and in which the same reading is obtained irrespective of the pressure that is exerted. Furthermore, such micrometers have been more or less delicate devices, which would not withstand careless handling by an operator.

An object of my invention therefore, is to make a direct-reading micrometer in which the same reading may be obtained regardless of the pressure, which is exerted by the operator, and in which all of the delicate working parts are encased, and therefore fully protected against damage.

An additional object is to provide a micrometer in which the operating members exert a "pulling" as distinguished from a "pushing" force upon the movable jaw, thus relieving the C support of the usual stresses that tend to "spring" it apart. In this connection my invention includes a construction in which the forces which act upon the feeler and anvil occur on a line that is coincident with the axes of the feeler and anvil, wherefore, the operator can detect, through his sense of touch, whether or not the tool is being held at right angles to the work. This is important, for otherwise an imperfect reading would be obtained.

A further object of my invention is to make a micrometer in which the wear on the points may be taken up by means of an adjustment mechanism, wherefore the points need not be accurately machined.

Referring now to the drawing, Fig. 1 is a side elevation of a micrometer made in accordance with my invention; Fig. 2 shows a fragmentary elevation similar to that of Fig. 1, but with the feeler and anvil in contact with the work to be gauged; Fig. 3 is a section taken on the line 3—3 in Fig. 1; Fig. 4 is a top plan view of the micrometer.

The micrometer jaws, or points, comprise an anvil 10 and a feeler in the form of a plunger 11 which are disposed in axial alignment. The anvil, or relatively stationary jaw 10 is rigidly mounted on the lower arm of a C-shaped bar 12, the upper arm of which terminates in an extension 9, that has a passageway 13 therein in which the jaw 11 is slidably mounted. The rearward end of the bar 12 has an extension 14, rigid therewith, which operates as a handle for actuating the micrometer. The mechanism for moving the feeler 11 comprises a finger grip bar 15 which is pivotally mounted, at an intermediate point 16, to the handle extension 14, and is pivotally connected at 17, to a yoke 18. The yoke shown comprises a pair of plates that are disposed on each side of the support 12 and are rigidly connected through a pin 20 to the feeler 11. A slot 21 permits the pin to be moved with reference to the support 12, as may be observed from a comparison of Figs. 1 and 2.

The micrometer indicator is shown, as comprising a pointer 25 and a dial 26 which are mounted within a casing 27. The pointer is suitably attached by a mechanism, (not shown) to a stem 28, which is normally urged into contact with the upper end of the feeler 11, and the mechanism is so adjusted that when the stem is in contact with the anvil the indicator registers zero. The indicator and its associated internal mechanism may be purchased in open market so it need not be described in detail. It is sufficient however, to point out that by means of an adjusting screw 30, the position of the casing with reference to the support 12 may be adjusted, and then locked, so as to make the micrometer reading zero whenever the feeler and anvil are in contact. Thus, compensation may be made for any wear on the contacting points.

The normal position of the hand grips 14 and 15, is illustrated in Fig. 1, in which the stem and anvil are separated a maximum amount. The hand grips are urged apart by a spring 31 which is carried by the finger bar 15 and bears against the handle 14. Thus the micrometer is always available for use. If desired the finger grip part 15 may have a scale 40 on the lower edge thereof to facilitate measurement of the sheets of metal that are being gauged. In addition, if desired, a guard 41 may be mounted on the projection 9 so as to protect the micrometer housing.

An important advantage of the present invention is the fact that regardless of the pressure, which is exerted against the work, such pres-

sure is not imparted to the delicate parts of the indicator. A clearance slot 45 between the support 12 and the handle 14 assures the prevention of stress transmission through the support.

5 A further advantage is the fact that the operating forces exert a pulling action on the feeler against the anvil, and that such forces are as near as possible in alignment with the axis of the feeler and anvil. Thus, there is no tendency to spring the support 12 as is the case in the customary threaded type of micrometer.

10 An additional characteristic of the present invention is the fact that the micrometer dial is disposed in a plane at substantially right angles 15 to the axis of the feeler, thus the operator may make a pile of sheets and obtain a quick reading with minimum effort. In addition, the direct connection between the hand grip and the work engaging points enables an operator, by the sense 20 of touch, to adjust the plane of the tool so as to insure proper positioning of the points with reference to the work. For example, if the tool is not exactly at right angles to the work, or if a 25 small particle is lodged between the work and the points, such condition can be felt through the hand of an operator and the tool can be quickly turned to the proper position. Furthermore, if the foreign particle is compressible it can be 30 pressed to a point where it will not interfere objectionably with the reading, and yet, the crushing stresses will not be imparted to the indicator. Thus, the tool has rugged characteristics, and still has facilities for producing an extremely accurate reading.

35 I claim:—

1. In a measuring instrument of the class having a frame with spaced sides, aligned anvil and plunger members carried thereon at respective sides, and an indicator associated with the plunger; the novel arrangement wherein the indicator has an actuating part arranged to move with the plunger but not be moved by the plunger when the latter approaches the work, and there are means operatively connected with the plunger to move it, said means being secured to the frame only on the anvil supporting side of the frame, whereby the reactions on the frame, incident to forcing the plunger toward work positioned between the sides, will not tend to separate the sides 50 of the frame.

2. In a measuring instrument of the class described, a frame having a pair of spaced arms substantially rigid therewith, an anvil on one of the arms, a micrometric measuring device including a feeler mounted on the other arm for

movement toward and away from the anvil to measure work embraced by the feeler and anvil, an operating lever pivoted to the arm of the frame which carries the anvil, and a link connecting the lever to the feeler, whereby the feeler 5 may be brought into forcible engagement with said work.

3. A micrometer having in combination, an indicator, a frame therefor, a work engaging stem 10 slidably mounted in one portion of the frame for actuating the indicator, said indicator having an actuating part that moves with the stem but is not moved thereby as the stem approaches the work, an anvil in alignment with the stem, and carried by another portion of the frame for engagement with work opposite the stem, and means 15 for moving the stem toward the anvil, said means being connected with the frame on the anvil carrying portion of the frame only, whereby the operation of said means will not tend to substantially force the anvil out of position with respect to the indicator irrespective of the magnitude of force applied to said means.

4. A measuring instrument having in combination a yoke-type frame, aligned fixed and movable measuring members mounted on opposite arms of the yoke, indicating means operatively connected with the movable member, a handle connected with and extending from the yoke arm of the frame which carries the fixed measuring 25 member and in a direction substantially normal to the axes of said measuring members, a finger grip bar pivotally mounted on the handle adjacent the last mentioned yoke arm, operating means connecting the grip bar to said movable 30 member for moving the movable member toward the fixed member, the points of connection between the operating means and the finger grip bar and movable member lying substantially in a plane which is coincident with the axes of said 35 fixed and movable measuring members.

5. In a micrometer, having a frame with spaced parts, aligned fixed and movable measuring members carried respectively on said parts for engagement with the work, indicating means operatively connected with the movable member, operating means for moving the movable member toward the fixed member, said operating means being pivotally mounted on the part of the frame which carries the fixed member, and connecting 45 means pivotally secured to the operating means and movable member in a plane coincident with the axes of said measuring members.
